UNITED STATES PATENT OFFICE

172,219

COMBINATION FIRE TRUCK AND AMBULANCE

Edward C. Califano, New York, N. Y.

Application November 6, 1953, Serial No. 27,482

Term of patent 7 years

(Cl. D14—3)

To all whom it may concern:

Be it known that I, Edward C. Califano, a citizen of the United States, residing at New York, State of New York, have invented a new, original, and ornamental Design for a Combination Fire Truck and Ambulance, of which the following is a specification, reference being had to the accompanying drawing, forming a part thereof.

Fig. 1 is a side elevational view of the combination fire truck and ambulance, showing my new design,

Fig. 2 is a front elevational view thereof, and Fig. 3 is a rear elevation view thereof.

I claim:

The ornamental design for a combination fire truck and ambulance, as shown.
